UNITED STATES PATENT OFFICE.

FRANK J. TONE, OF NIAGARA FALLS, NEW YORK.

METHOD OF HEATING CARBON.

961,912.

Specification of Letters Patent. Patented June 21, 1910.

Application filed February 4, 1907. Serial No. 355,745.

To all whom it may concern:

Be it known that I, FRANK J. TONE, of Niagara Falls, Niagara county, New York, have invented a new and useful Method of Heating Carbon, of which the following is a full, clear, and exact description, reference being had to the accompanying drawing, forming part of this specification, in which the figure is a sectional side elevation showing one form of furnace for carrying out my invention.

My invention relates to the electric heating of carbon, for the purpose of baking, purifying, polymerizing, graphitizing, or otherwise changing its character by heat treatment. Heretofore in carrying out this heat treatment, an electric furnace of the resistance type has been employed; and the resistance conductor has consisted either of the carbon material to be heated or of an independent carbon conductor, or of both used jointly. While fairly satisfactory results have been obtained by such methods, I have discovered that the efficiency of the process may be greatly increased by applying the electric arc method of heating.

In the preferred form of my method, the arc is formed within the mass of the carbon material, and the heat of the arc is transmitted into said mass.

In the drawing, I show a receptacle 2 formed of refractory material and containing the charge 3 of carbon to be treated.

4 and 5 are the upper and lower electrodes, 35 which are shown as vertically disposed at the central part of the charge, the lower one projecting through the bottom of the receptacle. I have shown the upper electrode as surrounded by a shield 6 of carbon or other refractory material, which may be suspended from the carbon holder 7 but is insulated therefrom by a refractory insulating layer 8.

When the electric current is supplied, an arc is established between the electrodes 4 and 5, and within the mass of carbon; and the heat thus generated is transmitted outwardly to the surrounding mass, thus baking, purifying, graphitizing, or giving the heat treatment desired. During this action, 50 the shield for the upper electrode prevents contact between the charge and this electrode, and thus avoids shunting of the current around the arc, which would give ordinary resistance heating of the carbon charge.

55 The advantages of my invention result from the peculiar method of heating by con-

duction convection or radiation from the arc. An increase of efficiency is thus obtained over resistance heating, this being due to the greater amount of energy which can be generated, and supplied to a given volume of charge in a given time. In a furnace of the resistance type, a large mass of charge is heated in a single operation which must therefore extend over a comparatively long period of time. Radiation losses are directly proportional to the time of heating and are therefore large. The loss of energy in heating the mass of charge, outside of the effective heating zone, is large on account of the comparative slowness of energy production and supply. In the arc furnace, the productive heat energy constitutes a much larger proportion of the total energy because the reaction zone being smaller, the heating of a given mass can be accomplished in a much shorter period of time. For similar reasons, it is possible with arc heating, to generate higher temperatures with the same electrical horse power, than with resistance heating, and this is of considerable importance in the production of graphite of certain grades. When carbon or graphite is heated to the intense heat of the electric arc, not only are its physical characteristics changed, but any other substances such as silica, alumina, iron, calcium, etc., which may be commonly associated with it as impurities, are volatilized and driven out of the zone of high temperature. Such purification of carbon and graphite may be carried out in the arc process herein described, with great efficiency and economy.

I do not confine myself to the particular arrangement or number of electrodes shown in the drawing and many other arrangements may be used and will readily occur to those skilled in the art, which will accomplish the objects of the invention, it being essential that the charge of carbon does not come in contact with at least one of the electrodes and that the arc is operated within the mass of carbon treated. The method may be applied to the heating of any carbon articles and various carbonaceous materials; and the form of the furnace, electrodes, etc., may be varied widely without departing from my invention.

I claim:—

1. The method of heating carbon, consisting in forming an electric arc within a charge composed of carbonaceous material,

thereby heating such material by transmission of heat from said arc; substantially as described.

2. The method of heating carbon, consisting in forming an electric arc between electrodes and within a charge composed of a mass of carbon, preventing any substantial contact between the carbon and one of the electrodes, and transmitting the heat of the arc into the carbon mass; substantially as described.

3. The method of polymerizing carbon, consisting in establishing an electric arc within a charge composed of carbon, and substantially preventing the charge from contact with one of the electrodes, thereby heating the charge by transmitting the heat from the arc therein into such charge; substantially as described.

4. The process of graphitizing carbon, consisting in establishing an electric arc within a mass of said carbon, and transmitting the heat of said arc to the carbon to a sufficient

amount to at least partially convert the same into graphite; substantially as described.

5. The method of purifying graphite, which consists in forming an electric arc within a mass of impure graphite and between electrodes, preventing any substantial contact between the carbon and one of the electrodes, and transmitting the heat of the arc to the graphite mass sufficiently to volatilize the impurities and allowing the volatilized products to escape from the graphite; substantially as described.

6. The method of heating carbon, consisting in embedding an electric arc within a charge composed of a mass of carbon, and heating the carbon by transmission of heat therefrom; substantially as described.

In testimony whereof, I have hereunto set my hand.

FRANK J. TONE.
